UNITED STATES PATENT OFFICE.

ROBERT F. NICHOLS, OF ALTURAS, CALIFORNIA.

POWER-TRANSMITTER.

SPECIFICATION forming part of Letters Patent No. 629,461, dated July 25, 1899.

Application filed April 25, 1898. Serial No. 678,813. (No model.)

To all whom it may concern:

Be it known that I, ROBERT FLEETWOOD NICHOLS, a citizen of the United States, residing at Alturas, in the county of Modoc and State of California, have invented certain new and useful Improvements in Power-Transmitters; and I do hereby declare the following to be a full, clear, and exact description of the invention, such as will enable others skilled in the art to which it appertains to make and use the same.

My invention relates to improvements in apparatus for transmitting power, the same being specially applicable to use in operating lift or suction pumps.

The object of the invention is to provide simple and inexpensive mechanism whereby rotary motion transmitted from a suitable source of power is converted into reciprocating motion for operating the piston-rods of pumps and recovering the lost power of rotary motion when working suction or lift pumps.

The invention consists of a framework made up of suitable material to make a sufficient support for the machine, on which is mounted in suitable bearings a walking-beam, receiving power through a driving-rod from any suitable source. At the short side of the walking-beam are suitable openings at graduated distances, the openings being used to increase or to diminish the length of stroke of the pump-rods and to receive pins to connect the pump and driving rods. At the long side of the walking-beam, attached by a suitable coupling, is a balance-weight. A rod with couplings at each end is used to connect the walking-beam, the pump-rod, and the connecting-arm, and a post with couplings to pivot the connecting-arm, the connecting-arm having suitable openings at each end to pivot the post and couple with the diagonal and perpendicular pump-rods.

The invention also consists in other details of construction and combination of parts, which will be hereinafter more fully described and claimed.

In the drawings forming part of the specification, Figures 1, 2, 3, and 4 are perspective views of the invention. Fig. 5 is a detail end view of a coupling.

Similar reference letters and numerals indicate similar parts in all the views.

By referring to the drawings it will be seen that the framework is made up of timbers placed at an angle to form a brace, and cross-pieces, on which is mounted in suitable bearings the shaft 2, on which is mounted a walking-beam 3, so that it has one long end 9 and one short end 12, which receive power and motion through a rod 4. The walking-beam 3 through an opening in its short end 12, the mill-rod 4, and the pump-rod 11 are connected by suitable couplings C and pins. The walking-beam 3 at the long end 9 has an opening to receive a suitable fastening 9', to which is connected a weight 10. It will be plainly seen that by the downward stroke of the mill-rod 4 the weight 10, connected to the walking-beam 3, will be raised, while in the upward stroke of the mill-rod 4 the weight 10 will descend and the pump-rod 11 will be raised. The weight 10 in its descent will raise an amount of water equal to its weight, thus taking off part of the strain from the mill and enabling the mill to raise water from a greater depth.

Fig. 2 is another view of the machine, showing how the stroke of the pump is increased. In this view the pump-rod 11 is connected to the walking-beam 3 at the opening 12 by a coupling 7 and a pin 6. The mill-rod 4 is connected by a coupling and pin to the walking-beam 3 at the opening 13 between the shaft 2 and the opening 12. The weight 10, connected to the walking-beam 3, is placed in the same position as in Fig. 1.

In Figs. 3 and 4 the frame is the same as in Figs. 1 and 2, but has one upright post 18 in addition. Said figures show a construction to increase the stroke of the pump when the pump stands in a perpendicular line with the windmill-rod, as in Fig. 1. The mill-rod 4 is coupled to the walking-beam 3 a distance from the shaft 2 equal to the stroke of the mill and directly perpendicular to the pump 20. A rod 14, with couplings at each end, is connected diagonally to the walking-beam 3 at the point 12 with a pin 6 and the pump-rod 11 at the coupling 15. One end of a connecting-rod 16 is passed through the couplings 7 and 15, secured by a pin 17. The other end

of the connecting-rod 16 is pivoted to a post 18 by a pin through a coupling 19. At the long end of the walking-beam 3 at the point 9 is hung a weight 10, the same as shown in Figs. 1 and 2 and for the same purpose.

What I claim is—

1. In a device for transmitting motion, a supporting-frame, a walking-beam pivoted on said frame, said walking-beam having a series of adjusting-holes on its short side, a balance-weight attached to the long side, a pump-rod, means for connecting said pump-rod to said walking-beam, a windmill-rod, and a connection between said rod and said walking-beam, substantially as described.
- 15 2. In a device for transmitting motion, a supporting-frame, a walking-beam pivoted to

said frame, a series of adjusting-holes in the short side of said walking-beam, a windmill-rod connected to said walking-beam, a balance-weight on the long side of said walking-beam, a pump-rod in a line vertically with the windmill-rod, a vertical post secured to the frame-base, a link connecting said pump-rod and said post, a connecting-rod adjustably connected with the walking-beam and also connected to said pump-rod, and pivot-pins connecting said parts, substantially as described.
